UNITED STATES PATENT OFFICE.

JOHN ROGERS FLANNERY, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,276,744.

Specification of Letters Patent. Patented Aug. 27, 1918.

Application filed February 19, 1916. Serial No. 79,391.

To all whom it may concern:

Be it known that I, JOHN ROGERS FLANNERY, a citizen of the United States, and a resident of Pittsburgh, in the county of 5 Allegheny and State of Pennsylvania, have invented certain new and useful Improvements in Stay-Bolt Structures; and I do hereby declare the following to be a full, clear, and exact description of the invention, 10 such as will enable others skilled in the art to which it appertains to make and use the same.

This invention relates to an improvement in staybolt structures.

15 Some stay bolts have a tell tale hole or bore extending throughout the length of the bolt and open at both ends. In others the hole extends from each head part way only, through the bolt. When a bolt breaks or is 20 fractured, the steam passes through the tell tale and indicates to the fireman that the bolt has been injured. These tell tale holes being open at the ends, form pockets in which the dust and cinders accumulate and 25 clog thus necessitating a cleaning out of the holes at intervals, at times quite frequently and this invention consists in sealing the ends of the holes thus preventing the entrance and accumulation of dust and other 30 matter in the holes, but permitting of the forcible ejection or removal of the seals in the event the bolt should be broken or ruptured, so that the steam or water as the case may be, will have free egress through the 35 head or end of the bolt.

The invention further consists in a stay-bolt for boilers having inclosed therein a material which is sensitive to the action of water to denote the condition of the bolt.

40 The invention further consists in certain features of construction and combinations of parts as hereinafter set forth and pointed out in the claims.

In the accompanying drawings, Figures 45 1, 2, 3 and 4 are views in elevation partly in section of several embodiments of my invention.

In Fig. 1 I have shown an ordinary rigid stay bolt 5 with a tell tale hole 6 at each end 50 and in Fig. 2 show the tell tale extending throughout the length of the bolt.

The holes are closed or sealed at their outer ends by plugs as at 7 made of metal or packing of any kind that will not be

burned out by the fire or heat; which will 55 prevent the entrance of dust or cinders to the holes and insure the composition in the holes being kept dry.

The composition represented at 8, is composed of ingredients such as caustic alkali, 60 metallic sodium, etc., which when moistened with water will rapidly generate a gas, which expanding, forces out the seals or plugs, and which acting on certain metals, such as aluminum and Babbitt metal (of 65 which the closures of the tell-tale hole may be made), will instantly break down or disintegrate them thus opening up the tell tale holes for the free passage of the steam or water.

If therefore a bolt constructed as above 70 should fracture, the steam or water as the case may be, coming in contact with the composition in the tell tale hole, instantaneously generates a gas which expands and forces out 75 the seals at the ends of the holes, the expansion of the gas being more rapid than could be taken care of by a back flow of the gas through the crack caused by the fracture, or as stated above instantly disintegrates or 80 dislodges the seals. As soon as the seals are blown off or out or otherwise dislodged by the reaction within the bolt, the steam or water as the case may be, will be free to flow out through one or both ends of the bolt 85 and indicate to the fireman or engineer that the bolt is fractured.

When the improvement is applied on a flexible stay bolt as in Fig. 3, I provide the cap 9 of the bolt with a central opening 90 closed by a soft metal closure 10 which can be readily dislodged by a blow from the inside, and instead of closing the hole with a seal, as in the previous figures, I prefer to employ a loose fitting plunger 11 of hard 95 metal inserted within the hole a distance sufficient to leave a space for a packing 12, which may be a hard grease. The hole behind the plunger is filled with the composition as in the previously described devices. 100 The construction shown in Fig. 4 is the same as in Fig. 3 except that the plunger is provided with a pin 13 for more readily dislocating or breaking the soft metal closure for the opening in the cap. With these constructions shown in Figs. 3 and 4, it will be seen that when the composition is moistened by steam or water entering the tell-

tale hole through a crack in the bolt the plunger will be forcibly ejected against the soft metal closure and dislodged or rupture the same and allow of the free escape of steam or water and thus indicate a fracture of the bolt.

I would have it understood that by the term "dislodge" used in the claims, I intend to include not only the forcible removal of the seals but also their disintegration.

I would also have it understood that I do not confine myself to details, but on the contrary claim broadly a tell tale hole carrying a composition which on exposure to steam or water will set up a reaction that will free the composition and permit it to escape thus opening up the tell tale to the free passage of steam or water.

It will be apparent that the material employed within the tell-tale hole will be such as shall be sensitive to the action of water or steam to denote the condition of the hole.

Having fully described my invention what I claim as new and desire to secure by Letters-Patent, is:—

1. A stay bolt for boilers having inclosed therein, a material which is sensitive to the action of water to denote the condition of the bolt.
2. A stay bolt having a tell-tale hole, and material freely disposed in said tell-tale hole, said material being sensitive to the

action of water to denote the condition of the bolt.

3. A stay bolt for boilers having a tell-tale hole therein, a seal covering the outer end of said hole and a composition within the hole, which when exposed to water or steam entering the hole through a fracture in the bolt will set up a reaction sufficient to dislodge the seal.

4. A stay bolt for boilers having a tell-tale opening, a metal seal forming a closure for said opening, and material within said tell-tale opening which will when exposed to moisture, set up reactions which will break down or disintegrate said metal closure.

5. In a stay bolt structure, a stay bolt having a tell-tale opening, a bearing for the head of said bolt, and a cap over the head of the bolt, said cap having an opening, a metal closure for the opening in the cap, and material in said tell-tale opening which will, when exposed to moisture, set up reactions which result in the breaking down, or disintegrating of said closure in the opening in the cap.

In testimony whereof, I have signed this specification in the presence of two subscribing witnesses.

JOHN ROGERS FLANNERY.
